Filed Jan. 22, 1965, Ser. No. 83,529

Term of patent 14 years

(Cl. D62—2)

FIG. 1

FIG. 2

FIG.3

FIG.4

FIG. 1 is a perspective view showing the front, the top and one side of the casing embodying my new design;

FIG. 2 is a bottom view of the casing of FIG. 1 shown partially broken away for convenience of illustration;

FIG. 3 is an elevational view of the back of the casing of FIG. 1; and

FIG. 4 is a top view of the casing of FIG. 1.

The unseen side of the casing, opposite to the side seen in FIG. 1, is identical in appearance to the side seen in this figure.

The dominant features reside in the solid line portion.

I claim:

The ornamental design for a casing for combined ion generating and air filtering unit, as shown and described.
